UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

AUTOMOBILE MACHINERY.

1,316,998.

Specification of Letters Patent. Patented Sept. 23, 1919.

Application filed November 19, 1914. Serial No. 872,916.

To all whom it may concern:

Be it known that I, JOSEPH BIJUR, a citizen of the United States, and residing at 122 East 60th street, New York, in the county of New York and State of New York, have invented new and Improved Automobile Machinery, of which the following specification is a full disclosure.

This invention relates to automobile machinery, although certain features thereof are applicable in other relations.

One of the objects thereof is to provide simple and compact disposition of parts whereby a dynamo is effectively connected with an internal combustion engine.

Another object is to provide apparatus of the above type in which the dynamo is maintained in most efficient condition without complicating the form or arrangement of the parts.

Another object is to provide apparatus of the type first mentioned in which the power transmitting elements are adapted to meet the hardest use without injury.

Other objects will be in part obvious from the annexed drawings and in part indicated in connection therewith by the following analysis of this invention.

This invention accordingly consists in the features of construction, combinations of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views of which:

Figure 1 is a front sectional elevation of an automobile engine, the section being taken along the line A—A of Fig. 2.

Fig. 2 is a sectional plan taken substantially along the line B—B of Fig. 1.

Fig. 3 is a detail plan of gearing, certain parts being cut away in order to show the construction more clearly.

Fig. 4 is a semi-diagrammatic side elevation of the parts shown in Fig. 1 on a reduced scale.

55

Fig. 5 is a side view of portions of a dynamo, certain parts being cut away along a central plane in order to show the construction more clearly.

Referring now to Fig. 4 of the drawings, there are indicated at 1 and 2 the cylinders of a multiple-cylinder internal-combustion engine in which the crank shaft 3 is driven by the cranks 4 and in turn drives a clutch 5 of any desired type. Forwardly from the engine, the crank shaft has secured thereon a spiral gear or worm wheel 6 and another gear or worm 7 and thence passes through end wall 8 and the radiator, 9 being provided with a pulley 10 which drives by 60 means of a belt 11 the propeller fan 12 discharging rearwardly toward the engine.

Meshing with gear 7, as indicated in Fig. 1 of the drawings, is a gear 13 which drives a cam shaft 14 at one-half the angular rate 65 of speed of the crank shaft 3 and which is provided with the ordinary cams for actuating the valves of the engine, not here shown as they form in themselves no part of the present invention.

80

The spiral gear 6 meshes with a spiral gear 15 upon the armature shaft 16 of a dynamo 17, hereinafter described. It may here be noted that by the term "spiral gear" is meant a gear in which the teeth are inclined 85 with respect to its axis of rotation in a direction other than that of elements of a cone about the said axis. In other words, the teeth of such a gear, as the term is herein used, lie substantially in a cylindrical surface about its axis of rotation and yet are inclined in non-parallel relation to such axis. The form of spiral gearing herein shown is substantially that of a worm and wheel, the pitch of the threads or teeth preferably being such that the gearing is reversible and either gear may be used to transmit power to and drive the other.

90

Extending about crank shaft 3 and the several gears above mentioned, is a casing 18 known as the crank-case containing heavy oil to such a depth as to substantially submerge the gearing. This casing is provided with a relatively detachable upper portion

95

19 through which the shaft 16 and other parts pass, thus tending to hold them in alinement. It may be noted, moreover, that the casing is separable into other portions in 5 order to permit the ready assembling or removal of the parts, but it is believed unnecessary to show here the details of the various portions and means by which they are secured together. It may be noted at this 10 point, however, that the casing serves not only to aid in holding the parts in position but maintains the gearing in well lubricated and quiet running condition without the chance of oil working into the vulnerable 15 portions of the dynamo.

The teeth of the gear 6 are so curved in a direction parallel to the crank shaft, as is indicated in Fig. 3 of the drawings, that a slight endwise movement of the gear may be 20 permitted without tending to bind the teeth of gear 15 meshing therewith. This is accomplished by making the radius of curvature of the teeth of gear 6 in a direction lengthwise of the crank shaft greater than 25 the radius of curvature in that location of the teeth of gear 15. A material lateral movement of gear 6, however, is prevented by mounting it upon the splined collar 20 which is secured to the crank shaft 3 in such 30 manner as to permit an endwise movement of the latter without imparting a corresponding movement to the gear. The hubs of gear 6 are preferably engaged by the bearing collars 21 which are fast upon the 35 casing 18 or other part of the engine frame. In this manner the clutch 5 may be thrown in and out with any desired degree of force without tending to cramp the above spiral gearing.

40 Referring now to Fig. 5 of the drawings, there is shown somewhat in detail the construction of dynamo 17.

The latter preferably takes the form of a machine adapted to act either as a motor 45 or generator, although certain features of this invention may be embodied in apparatus in which either a motor or a generator be separately used. The armature shaft 16 passes at the lower end of the generator 50 through a double thrust bearing 22 substantially opposite the casing portion 19. This bearing is formed by providing a collar 23 fast upon the shaft 16 and having raceways 24 and 25 for the balls 26 and 27. The mating raceway for the set of balls 27 is formed in a collar 28 and in like manner a collar or ring 29 provides an outer raceway for the balls 26. These outer raceways are gripped by a flanged ring 30 and firmly held within 55 the tubular extension 31 of the dynamo head. A ring 32 threaded upon the shaft 16 aids in holding the inner bearing member in position and the outer bearing members are supported by a ring 33, which is in turn 60 held in position by a flanged collar 34

threaded upon the dynamo head at 35. In this manner there is provided a bearing which not only permits free rotation of the shaft but is well adapted to resist a thrust in either an upward or downward direction, 7 according as the dynamo is driving or being driven from the engine.

The upper end of shaft 16 rests within a ball-bearing 36. The ample lubrication of this bearing without the chance of the oil 7 running downwardly into the armature or possibly the commutator of the dynamo, is highly desirable and is accomplished by means of a flanged ring 37 which receives and deflects from the shaft the oil dripping 8 from the bearing immediately above the same. This oil so diverted passes into an annular passage 38 and is thence drained away through a passage 39 to a point outside the dynamo casing. In this manner the 8 dynamo may be used in an upright position without the chance of injury and yet will be maintained in a well lubricated condition. It will also be seen that this arrangement not only provides a compact disposition but 9 permits the gear 15 to be well lubricated without the necessity for providing a stuffing box or other tight connection at the point where the shaft passes through the casing. 9

The operation of the above described apparatus is substantially as follows:

Assuming that dynamo 17 takes the form of a motor generator and that it be desired to start the engine, the current is passed 1 from a suitable storage battery to rotate the shaft 16. This action causes the turning over of the crank shaft with compression in the engine cylinders, and upon the engine starting, power is transmitted therefrom to 1 the dynamo 17 which now runs as a generator and charges the storage battery from which it received current when acting as a motor. The dynamo 17, being positioned in the path of discharge of the fan 12, is maintained in cool condition even though acting under heavy load and its double thrust bearing permits it either to drive or be driven without tendency to displace its shaft. It will also be noted that by the disposition of 1 the dynamo as above noted upon the opposite side of the crank shaft from the cam shaft 14, each is balanced to a large extent by the other; a point of considerable advantage in light vehicles in which the 1 crank shaft runs lengthwise substantially at the center of the vehicle.

It will thus be seen that there is provided apparatus in which the several objects of this invention are achieved.

As many changes might be made in the above construction, and as many apparently different embodiments might be made of this invention without departing from the scope thereof, it is intended that all fea- 1

tures herein described or shown in the accompanying drawings shall be interpreted as illustrative and not in a limiting sense.

Having thus revealed this invention, I claim as new and desire to secure the following combinations of elements, or equivalents thereof, by Letters Patent of the United States:—

1. In apparatus of the class described, in combination, an internal-combustion engine, a dynamo, spiral gearing connecting said dynamo and the crank shaft of said engine, said gearing comprising a spiral gear on said crank shaft and a spiral gear connected with said dynamo, and means adapted to permit an endwise movement of said shaft relative to the member of said spiral gearing mounted thereon whereby cramping of the spiral gearing is avoided.
2. In apparatus of the class described, in combination, an internal-combustion engine, a dynamo, a spiral gear upon said dynamo and a spiral gear upon the crank shaft of

said engine meshing with said first spiral gear and having a greater radius of curvature of its path in a direction parallel to said crank shaft than that of the teeth meshing therewith in said direction.

3. In apparatus of the class described in combination, an internal combustion engine, a dynamo, a worm upon the shaft of said dynamo, a coöperating worm wheel upon the crankshaft of said engine, the radius of curvature of said worm being smaller than that of the concavity of the periphery of said worm wheel, said worm wheel being splined to said crankshaft, to permit a limited endwise movement of said crank-shaft relative to said worm wheel.

In witness whereof I hereunto subscribe my name, as attested by the two subscribing witnesses.

JOSEPH BIJUR.
